UNITED STATES PATENT OFFICE

153,568

DESIGN FOR A TRANSFER SHEET OF
WEATHER MAP SYMBOLS

Edward L. A. Wagner, New York, N. Y.

Application December 16, 1946, Serial No. 135,547

Term of patent 14 years

(Cl. D25—1)

To all whom it may concern:

Be it known that I, Edward L. A. Wagner, a citizen of the United States, residing at New York city, in the county of New York and State of New York, have invented a new, original, and ornamental Design for a Transfer Sheet of Weathermap Symbols, of which the following is a specification, reference being had to the accompanying drawing, forming part thereof.

The drawing discloses a view of a transfer sheet of weathermap symbols, showing my new design.

I claim:

The ornamental design for a transfer sheet of weathermap symbols, as shown.

EDWARD L. A. WAGNER.
